UNITED STATES PATENT OFFICE.

WILLIAM H. FULCHER, OF OAKLAND, CALIFORNIA, ASSIGNOR TO FULCHER PULP BOTTLE COMPANY, OF OAKLAND, CALIFORNIA, A CORPORATION OF CALIFORNIA.

PROCESS OF AND APPARATUS FOR MAKING PAPER HOLLOW WARE.

1,280,008.

Specification of Letters Patent. Patented Sept. 24, 1918.

Application filed January 3, 1916. Serial No. 69,839.

To all whom it may concern:

Be it known that I, WILLIAM H. FULCHER, a citizen of the United States, residing at Oakland, in the county of Alameda and 5 State of California, have invented new and useful Improvements in Processes of and Apparatus for Making Paper Hollow Ware, of which the following is a specification.

The object of the present invention is to 10 provide an improved process of, and apparatus for, making paper milk bottles.

In the accompanying drawing, Figure 1 is a vertical section of the machine, certain parts being shown in side elevation; Figs. 15 2, 3 and 4 are horizontal sections on the lines 2—2, 3—3, 4—4 respectively of Fig. 1; Fig. 5 is a perspective view of an eccentric pivot pin.

Referring to the drawing, 1 indicates a 20 hollow metal core, finished on the outside to the form of the inside of the bottle to be made, open at the bottom and having an apertured top 2. Said top 2 is formed with a central inwardly extending apertured boss 25 3, and in said boss 3 is screwed one end of a solid shaft 5, around which is a sleeve 6, having at its lower end four pairs of outwardly extending parallel arms 7, having at their outer ends holes 8 to receive pivot pins 30 9. 11 indicates levers formed with bearings 12 each adapted to be received within a pair of the arms 7 and to receive the pivot pins 9 passed through said arms, whereby said levers are pivoted upon the arms. Plates 13 35 form part of the levers 11 at their lower ends and have therethrough vertically extending holes 14 which enable them to be bolted to compressor sections 16. At its upper end each lever is formed with a bearing 17 to 40 receive the central portion 18 of a pivot pin 19. The terminal portions of said pivot pins extend eccentrically from the central portion thereof, so that the position of said terminal portions with reference to the lever 45 11 can be adjusted slightly in said bearing 17 by turning said central portion 18 in said bearing, since said bearing 17 is slit longitudinally and has extensions 21, by which the bearings 17 can be clamped about the 50 central portion 18 by means of a screw 22 screwed through one extension 21, its head bearing against the other extension. The terminal portions of each pivot pin 19 are connected to ends of links 23, the other ends

of which are pivotally connected in pairs to 55 the free ends of arms 24, extending radially from a sleeve 26 around the sleeve 6, and having a circular groove 27 therearound to enable it to be conveniently moved on the sleeve 6. It will be readily understood that 60 by raising and lowering the sleeve 26 upon the sleeve 6 and by thus moving upward the inner ends of the links 23, the outer ends of said links, and therefore also the upper ends of said levers, are drawn inwardly, thus 65 causing the lower portions of said levers and the compressor sections rigidly secured thereto to swing outwardly.

Each compressor section is formed with a plurality, here shown as three, of vertical 70 ribs 28, integrally connected by horizontal mediate ribs 29 and upper and lower terminal plates 31, 32, the ends of which plates extend beyond the outer vertical ribs, the upper plate 31 having holes therethrough to 75 enable it to be bolted to the corresponding lever 11, as hereinbefore described. The inner edges of the vertical ribs 28 are formed near their respective ends with recesses 33, 34, the upper recesses registering 80 with the upper closed end of the core 1, which projects slightly beyond its side. To the inner edges of the vertical and horizontal ribs of each compressor section is secured a screen section 36, preferably of woven 85 wire, which screen section at its upper and lower portions has grooves 37, 38 corresponding with the recesses 33, 34, the upper groove 37 serving, with the closed end of the core, which projects slightly beyond the 90 core, to form at the upper end of the paper bottle a circular groove in its inner surface, to enable the bottom of the bottle to be readily secured thereto. The lower groove 38 in the wire screen section is for 95 the purpose of forming a bead around the neck of the bottle near its mouth for the purpose of capping the same with an external cap.

The apparatus is used in the following 100 manner:—The sleeve 26 is first raised on the sleeve 6, thus swinging outwardly the compressor sections. Retaining the parts in this position the whole of the apparatus is lowered into a vessel containing paper pulp. 105 The sleeve 26 is then lowered to its original position upon the sleeve 6, thus causing the compressor sections to move inwardly to-

ward the core 1, and compressing between the sections and the core the pulp which is intervening therebetween. During the compression the water contained in the pulp 5 escapes through the perforations in the screen sections leaving the solid matter between the screen and the core. The apparatus is now drawn out of the vessel containing the pulp, such of the pulp as has 10 entered the interior of the core, and passed through the holes in the upper closed end thereof, now falling back into the vessel. The sleeve 26 is now raised upon the sleeve 6, thus separating the compressor sections 15 from the core, and leaving the pulp in the shape of the bottle, except that, at the junctions between the compressor sections, there are formed on the pulp four longitudinal ridges. The shaft carrying the core is now 20 rotated slightly and the compressor sections are again closed by the core. This has the effect of smoothing out said ridges and also any irregularities in the outer surface of the paper bottle which have been produced in 25 the first compression. The operation of first removing the compressor sections from the pulp, then turning the core with the pulp thereon through a small angle, and then again compressing the compressor sections upon 30 the pulp, is repeated as many times as may be found necessary to produce a smooth exterior surface on the bottle.

While I have for the sake of brevity and clearness of description referred herein only 35 to the making of paper milk bottles, it is to be understood that the term "paper milk bottles" as used in the specification and claims is intended to include all kinds of hollow ware for which the invention is found 40 suitable.

I claim:—

1. The process of making paper hollow ware which consists in pressing paper pulp between a core and compressor sections, separating the compressor sections from the pulp, and again compressing the pulp by compressor sections applied to different parts thereof.

2. The process of making paper hollow ware which consists in dipping a core into a vessel containing paper pulp, causing compressor sections to approach the core and compress the pulp therebetween, raising the core and the sections with the pulp therebetween from the vessel containing the pulp, separating the compressor sections from the pulp, and again compressing the pulp by pressure applied to different parts thereof.

3. The process of making paper hollow ware which consists in dipping a core into a vessel containing paper pulp, causing compressor sections to approach the core and compress the pulp therebetween, raising the core and the sections with the pulp therebetween from the vessel containing the pulp,

separating the compressor sections from the pulp, and again compressing the pulp by means of compressor sections applied to different parts thereof.

4. In a machine for making paper hollow ware, the combination of a core, a shaft for said core, arms extending in a radial direction with reference to said shaft, levers pivoted on said arms, compressor sections secured to said levers, each having ribs, screen sections secured to the inner edges of said ribs, a sleeve around the shaft and links pivotally connected to said sleeve and to the levers.

5. In a machine for making paper hollow ware, the combination of a core, a shaft secured to said core, a sleeve on said shaft having at its lower end outwardly extending arms, levers pivoted on said arms, compressor sections secured to said levers, each having ribs, screen sections secured to the inner edges of said ribs, a second sleeve around the first-named sleeve, and links pivotally connected to said second sleeve and to said levers.

6. In a machine for making paper hollow ware, the combination of a hollow core, open at the bottom, a shaft secured to said core, a sleeve on said shaft having at its lower end outwardly extending arms, levers pivoted on said arms, compressor sections secured to said levers, each having ribs, screen sections secured to the inner edges of said ribs, a second sleeve around the first-named sleeve, and links pivotally connected to said second sleeve and to said levers.

7. In a machine for making paper hollow ware, the combination of a hollow core, open at the bottom, a shaft secured to said core, a sleeve on said shaft having at its lower end outwardly extending arms, levers pivoted on said arms, compressor sections secured to said levers, each having ribs, screen sections secured to the inner edges of said ribs, each lever having at its upper end a bearing, eccentric pivot pins each contained in one of said bearings, means for clamping said pin in the bearing, a second sleeve around the first-named sleeve, and links pivotally connected to said second sleeve and to eccentric portions of said pivot pins.

8. In a machine for making paper hollow ware, the combination of a hollow core, open at the bottom, and having an apertured top formed with a central apertured boss, a shaft, one end of which is screwed into said boss, a sleeve on said shaft having at its lower end outwardly extending arms, levers pivoted on said arms, compressor sections secured to said levers, each having ribs, screen sections secured to the inner edges of said ribs, each lever having at its upper end a bearing, eccentric pivot pins each contained in one of said bearings, means for clamping said pin in the bearing, a second sleeve

around the first-named sleeve, and links pivotally connected to said second sleeve and to the eccentric portions of said pivot pins.

9. In a machine for making paper hollow ware, the combination of a hollow core, open at the bottom, and having an apertured top formed with a central inwardly extending apertured boss, a shaft, one end of which is screwed into said boss, a sleeve on said shaft 10 having at its lower end outwardly extending arms, levers pivoted on said arms, compressor sections secured to said levers, each having vertical and horizontal ribs, screen sections secured to the inner edges of said 15 ribs, each compressor section and the corresponding screen section having grooves near

their upper and lower ends respectively, each lever having at its upper end a bearing, eccentric pivot pins each contained in one of said bearings, means for clamping said pin 20 in the bearing, a second sleeve around the first-named sleeve, and links pivotally connected to said second sleeve and to the eccentric portions of said pivot pins.

In testimony whereof I have hereunto set 25 my hand in the presence of two subscribing witnesses.

WILLIAM H. FULCHER.
